UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,129,593.

Specification of Letters Patent. Patented Feb. 23, 1915.

Application filed September 10, 1907. Serial No. 392,212.

To all whom it may concern:

Be it known that I, LANSING ONDERDONK, a citizen of the United States, residing at New York, in the county of New York, 5 State of New York, have invented certain new and useful Improvements in Loopoperating Mechanisms for Sewing-Machines, of which the following is a description, reference being had to the accompanying 10 drawing and to the letters and figures of reference marked thereon.

My invention relates to new and useful improvements in looper operating mechanisms for sewing machines, and has for its 15 object to provide a looper-operating mechanism which shall move the looper quickly into the needle loop and give thereto a dwell at the forward end of its stroke.

A further object of my invention is to 20 provide a looper-operating mechanism which shall move the looper across the path of the needle, whereby the looper thread loop is held spread for the entrance of the needle.

25 A still further object of my invention is to provide a looper-operating mechanism which shall consist of few parts, and shall be positive in its movements.

Still further objects will in part be obvious, and in part be hereinafter more fully 30 set forth.

In the drawings which show by way of illustration one embodiment of my invention,—Figure 1 is a front view partly in 35 section, with certain parts removed, of a sewing machine embodying my invention; Fig. 2 is a bottom plan view, showing my improved looper-operating mechanism; Fig. 3 is a detail perspective view, showing the 40 looper-operating mechanism and the looper thread controller; Fig. 4 is a diagrammatic view; showing in front view and side elevation, the position of the needle and the looper when the looper is at the forward 45 end of its stroke; and Fig. 5 is a similar view, showing the looper slightly retracted after the needle point passes the looper thread, so that the needle may clear the body of the looper.

50 The work support 1 has rising therefrom a standard 2, carrying an overhanging arm, supporting the needle head 3 at the forward

end thereof. The needle 4 is carried by a needle bar 5, which reciprocates in the needle head, and receives its movement from 55 a crank disk 6, through a link 7.

The needle thread controller consists of an arm 8 mounted on a link 7, which reciprocates the needle bar, and said arm 8 carries at its outer end thread guides 9 and 10. The 60 needle bar 5 is provided with a thread guide 11 at its upper end. Mounted at the upper end of the head of the machine on a bracket 12 is a thread-controlling lever 13, having a thread eye 14. Said thread-controlling 65 lever is connected by a link 15 to a collar 16 on the presser bar 17. The presser bar carries a presser foot 18 at the lower end. Said presser bar is lifted by the lever 19. Said presser bar is lifted by the lever 19.

The feed dog 20 is carried by a feed bar 70 21, which is pivoted at its rear end to a rock shaft 22, mounted in bearings on the under side of the work support, and receiving an oscillating movement from an eccentric strap 23, which is connected to an eccentric 75 on the main shaft mounted in the overhanging arm.

The feed bar is given its rising and falling movements from a rock shaft 24, carrying a crank arm 25, which extends into a yoke 80 26, mounted on the end of the feed bar 21. Said rock shaft 24 is oscillated by a yoke 27, secured thereto at its rear end, and engaging an eccentric on the shaft 28. The shaft 28 is connected to the rotary shaft, 85 mounted in the overhanging arm by a belt or other suitable connection 29. Through this connection the shaft 28 is given a continuous rotation.

In the present embodiment of my invention, I have shown the needle bar 5 as provided with two needles, (see Figs. 2 and 3), and coöperating with said needles are two loopers 30 and 31. Said loopers 30 and 31 are mounted in a looper carrier 32, which is 95 splined on a shaft 33. Said shaft 33 has one end thereof mounted in a bearing 34, at the forward end of the machine, and the other end of said shaft 33 passes through a bearing 35. The looper carrier 32 is yoke-shaped, as shown in Fig. 3, and the arms 36 of the yoke of said looper carrier are secured to the shaft 33, so that the looper may slide longitudinally on said shaft, but

partakes of the oscillating movements given to the shaft 33.

Between the arms 36 of the looper carrier is arranged a collar 37, which is rigidly secured to the shaft 33. The looper carrier is provided with a latch 38 having a lip 39, which when the looper carrier is in the position shown in Fig. 3, engages behind the collar 37, and holds the looper carrier with one of its arms in engagement with said collar 37. When it is desired to thread the looper, the latch 38 is lifted, drawing the lip 39 from behind the collar 37, and then said looper carrier may be slipped longitudinally of the shaft 33 to bring the loopers out from beneath the throat plate, whereby the same are rendered easily accessible for threading.

As a means for oscillating the looper-supporting shaft 33, I have provided an auxiliary shaft 40, mounted in suitable bearings underneath the work support. Said auxiliary shaft 40 is connected by means of a link 41, to a ball stud 42 carried on a crank arm 43 secured to the forward end of the rotary shaft 28. The opposite end of the auxiliary shaft 40 is provided with a crank arm 44, carrying a ball stud 45, to which is connected a link 46. The link 46 in turn is connected to a ball stud 47, secured to a crank arm 48, rigidly mounted on the shaft 33.

As the shaft 28 is rotated, the auxiliary shaft 40 will be oscillated as the length of the crank arm on said auxiliary shaft is greater than the length of the crank arm 43. As the auxiliary shaft is oscillated, the shaft 33 will also be oscillated through the link 46. The shaft 33 (see Figs. 2 and 3), extends through the bearing 35, and carries a collar 49 on its outer end which is provided with a ball stud 50.

The bearing 35 for the shaft 33 is slotted as at 51, and mounted in said slotted bearing is an arm or link 52. Said arm or link 52 is pivotally connected to the slotted bearing by a pivot pin 53. Said arm or link 52 engages the ball stud 50, carried by the collar 49 on the outer end of the shaft 33.

As the shaft 33 is oscillated, the collar 49, together with the ball stud projecting therefrom, will also be oscillated. The oscillations of the ball stud 50 about the axis of the shaft 33 will move the arm 52 toward and from the under side of the bed plate. As the outer end of the arm or link 52 moves toward the under side of the bed plate, it will also move away from the bearing 35, and as it is connected to the collar 49 on the shaft 33, said shaft 33 will be moved longitudinally. This longitudinal movement of the shaft 33 carries the loopers laterally, or cause the same to move in a curved path.

The timing of the parts is such, that as the

looper is moved forward, it is moved quickly into the needle loop and given a relative slow movement or dwell at the forward end of its stroke. As the looper moves forward into the needle loop, the looper-supporting shaft 33 is moved longitudinally, so that the looper is given a slight lateral movement as it enters the needle loop, and after the needle has moved up out of the path of the looper, the lateral movement of the looper continues, so that when the looper reaches the forward end of its stroke, it has moved practically across the path of the needle. The looper, therefore, at the forward end of its stroke has moved across the path of the needle (see Fig. 4), and the looper thread running to the previous stitch is held well to the opposite side of the needle path from the position of the looper when retracted. The crank 42 on the end of the shaft 28 is passing the slow dead center when the looper is at the forward end of its stroke and therefore, said looper will be given a dwell at the forward end of its stroke. The first retracting movements of the looper are comparatively slow so that the needle point passes the looper thread running from the eye of the looper to the previous stitch before the looper is retracted, but slightly. The looper however, is retracted sufficiently for the needle to pass between the body thereof and the looper thread above referred to, by the time the point of the needle reaches the plane of movement of the looper.

This machine may be readily adopted for use as a single thread chain stitch machine. A non-thread carrying looper is substituted for the thread carrying looper herein shown, and the looper carrier and looper are positioned so that the non-thread carrying looper will move in the opposite direction from that of the thread carrying looper. The screw 44', which holds the crank arm 44 on the shaft 40 is loosened and the arm turned half over and properly adjusted so as to give the correct timing for the movements of the non-thread carrying looper.

The slack in the looper thread is controlled by the thread cam wire 54, which is mounted upon a collar 55, secured to the looper shaft 33. This thread cam wire 54 moves between suitable thread guides 56 and 57 formed in the outer end of a thread wire 58, which is secured to the under side of the work support by a screw 59.

I do not claim herein broadly, the movements of the looper across the needle path to spread the looper thread as the same forms the subject matter of my application Serial No. 337,990, filed October 8th, 1906. The specific form of looper carrier and the looper thread controller are also disclosed in said application.

Having thus described my invention, what

I claim as new and desire to secure by Letters Patent, is:—

1. A sewing machine including in combination, a work support, a continuously rotating shaft mounted beneath said work support, a needle, a looper, a looper supporting shaft extending in substantially the same direction as said rotating shaft on which said looper is mounted, said rotating shaft and said looper supporting shaft being substantially in axial alinement, and means beneath the work support and intermediate said looper supporting shaft and said continuously rotating shaft for moving said looper forward into the needle loop, and laterally whereby said looper thread is positioned upon the opposite side of the needle, and for retracting said looper in the same path. 70
2. A sewing machine including in combination, an upper rotating shaft, a lower shaft continuously rotated from said upper shaft, a needle, a looper, a shaft for supporting said looper, and means for oscillating said looper supporting shaft from said continuously rotating shaft, and for moving the same longitudinally, said longitudinal and oscillating movements being timed to give said looper a forward movement into the needle loop, and a lateral movement to position the looper thread on the opposite side of the needle, and to retract said looper in the same path. 80
3. A sewing machine including in combination, a work support, a continuously rotating shaft mounted beneath the work support and terminating midway of said work support, a looper, a looper-supporting shaft extending in substantially the same direction as said rotating shaft on which the looper is mounted, said rotating shaft and said looper supporting shaft being substantially in axial alinement, means intermediate the rotating shaft and the looper-supporting shaft for oscillating said looper-supporting shaft, and means for moving said looper-supporting shaft longitudinally. 90
4. A sewing machine including in combination, a work support, a continuously rotating shaft mounted beneath the work support and terminating midway said work support, a looper, a looper supporting shaft on which the looper is mounted arranged substantially axially in line with said rotating shaft, and means intermediate said rotating shaft and said looper supporting shaft, for oscillating said looper supporting shaft, and means for moving said looper supporting shaft longitudinally. 100
5. A sewing machine, including in combination, a work support, a continuously rotating shaft mounted beneath said work support and terminating midway said work support, a looper, a looper support arranged substantially in line with said rotating shaft and said looper support for oscillating the same, and a link pivoted to a stationary part of the machine and connected to said looper support for moving said support longitudinally. 110
6. A sewing machine, including in combination, a work support, a continuously rotating shaft mounted beneath said work support and terminating midway said work support, a looper, a looper support arranged with its longitudinal axis substantially in line with said rotating means, an auxiliary shaft substantially parallel with the rotating shaft, means for oscillating said auxiliary shaft from the rotating shaft, means for oscillating the looper support from said auxiliary shaft, and means for moving the looper support longitudinally as it is oscillated. 120
7. A sewing machine, including in combination, a work support, a continuously rotating shaft mounted beneath said work support and terminating midway said work support, a looper, a looper support arranged with its longitudinal axis substantially in line with said rotating shaft, an auxiliary shaft substantially parallel with the rotating shaft, a link connecting said rotating shaft to said auxiliary shaft for oscillating the same, and a link for connecting the auxiliary shaft to said looper support for oscillating the same, and means for moving the looper support longitudinally as it is oscillated. 130
8. A sewing machine, including in combination, a work support, a continuously rotating shaft mounted beneath said work support and terminating midway said work support, a looper, a looper support arranged substantially in line with said rotating shaft, an auxiliary shaft substantially parallel with the rotating shaft, a link connecting said rotating shaft to said auxiliary shaft for oscillating the same, a link for connecting the auxiliary shaft to said looper support, an arm secured to the end of said looper support, a link pivoted to a stationary part of the machine and connected to said arm. 140
9. A looper mechanism including in combination, a looper, a looper support, means connected to the looper support for oscillating the same, and a link independent of said oscillating means, said link being pivoted to a stationary part of the machine at one end and connected at the other end directly to said looper support, and operated by the oscillating movement of the looper support to impart longitudinal movement to said support. 150
10. A looper mechanism including in combination, a looper, a looper support, means connected with the looper support for oscillating the same, a link pivoted at one end to a stationary part of the machine, a collar carried by said looper support, and having 160

an outwardly projecting arm connected to the other end of said link, whereby said link is operated by the oscillating movement of the looper support to impart longitudinal movement to said support.

11. A looper mechanism including in combination, a looper, a looper support, means connected to the looper support for oscillating the same, a link independent of said oscillating means, said link being pivoted at one end to a stationary part of the machine and disposed so as to vibrate in a vertical plane substantially parallel with the axis of the looper support, the other end of said link being connected to said looper support and operated by the oscillating movement of the looper support to impart longitudinal movement to said support.

12. A looper mechanism including in combination, a work support, a looper, a looper support, a collar carried by one end thereof, an arm formed on said collar, a link pivoted to the underside of said work support and connected to said arm, and means for oscillating said looper support, said link operating when oscillated by the movements of the looper support to impart longitudinal movement to said looper support.

13. A looper mechanism including in combination, a work support, a looper, a looper support, a collar carried by one end thereof, an arm formed on said collar, a link pivoted to the underside of said work support and connected to said arm, an arm carried by the looper support, and means connected with said last named arm for oscillating the looper support, the said link operating when oscillated by the movements of the looper support to impart longitudinal movement to said looper support.

14. A looper mechanism for sewing machines, including in combination a looper, a looper support, a rotary shaft, an auxiliary shaft, means for imparting motion from said auxiliary shaft to said looper support, and means for oscillating said auxiliary shaft from said rotary shaft, comprising a crank arm and means for adjustably securing said crank arm to said rotary shaft and means for moving the looper support longitudinally.

15. A sewing machine including in combination a work support, a continuously rotating shaft mounted beneath said work support, said rotating shaft having a crank at one of its ends, an auxiliary shaft parallel

to said rotating shaft, said auxiliary shaft having a crank at one of its ends longer than the first named crank, said cranks having direct connection between them, whereby said rotating shaft gives said auxiliary shaft an oscillatory movement, a looper support independent of said auxiliary shaft, and means for connecting said looper support to the auxiliary shaft.

16. A sewing machine including in combination, a work support, a looper carrier, a threaded looper mounted on said carrier, a rotary shaft, a rock shaft mounted on said work support, a link connecting said rotary shaft to said rock shaft, a link connecting said rock shaft to said looper carrier, and means connected to said looper carrier and operated through said rock shaft for moving the looper laterally.

17. A sewing machine including, in combination, a work support, a looper carrier, a looper mounted on said carrier, a rotary shaft, a rock shaft, a connection including a link between said rotary shaft and said rock shaft, a connection including a link between said rock shaft and said looper carrier, and an element pivoted to said looper carrier and to said work support whereby when said looper is oscillated the same is moved laterally.

18. In a sewing machine, the combination with a main shaft, of a needle bar carrying a needle, operative connections intermediate said needle bar and the main shaft, a looper rock shaft, a looper thereon coöperating with said needle in the production of stitches, a crank upon said looper rock-shaft, an operative connection intermediate said crank and the main shaft for rocking said looper shaft, a second crank upon the looper rock shaft, a fixed stud or abutment adjacent said looper rock shaft, and a link connection independent of the main shaft connection and intermediate the second named crank of said looper rock shaft and said fixed stud or abutment, whereby the rocking of said looper shaft produces through said link connection an endwise movement of said shaft.

In testimony whereof I affix my signature, in presence of two witnesses.

LANSING ONDERDONK.
